UNITED STATES PATENT OFFICE.

THEODOR SCHOU, OF MANSFIELD, OHIO, ASSIGNOR TO THE IDEAL ELECTRIC & MANUFACTURING CO., OF MANSFIELD, OHIO, A CORPORATION OF OHIO.

BRUSH-HOLDER.

1,378,565.

Specification of Letters Patent. Patented May 17, 1921.

Application filed July 14, 1920. Serial No. 396,251.

To all whom it may concern:

Be it known that I, THEODOR SCHOU, a subject of the King of Norway, and a resident of Mansfield, county of Richland, State 5 of Ohio, have invented certain new and useful Improvements in Brush-Holders, of which the following is a specification.

This invention relates to brush holder supports and especially to compound brush holders associated therewith of the tandem type adapted to provide a large area of positive brush contact distributed over a considerable segment on the collector rings, as required for instance in alternators and rotary converters, especially where relatively heavy 15 currents are to be provided for.

The main objects of this invention are to provide an improved and simplified form of such brush holders and supporting means 20 therefore; to provide improved means for mounting the same; to provide an improved form of connections for taking current to or from said brush holders, and the brushes carried thereby; to provide more effectively 25 against short circuits in the brush holder connections and against accidental breaks therein; and to provide a rigid housing for the conductors adapted to serve also as a support for the brush holders.

30 An illustrative embodiment of this invention is shown in the accompanying drawings in which—

Figure 1 is a plan showing parts of two collector rings disposed side by side, and a 35 pair of brush holders associated therewith and supported on arms stationarily mounted, it is to be understood, on the frame of machine which as a whole is not shown.

Fig. 2 is a front elevation of the forward 40 brush holder and a segment of the corresponding collector ring.

Fig. 3 is an irregular section taken on the line 3—3 of Fig. 1 extending through both a front and rear brush holder.

45 In the construction shown in the drawings, the brush holder frames 1 are each provided with a plurality of brushes 2. The brush boxes are provided with covers 3 which have threaded connection with the frame. Compression springs 4 are disposed between said 50 covers and the outer ends of the brushes to insure positive contact of the brushes with the corresponding ring. Each brush is provided with a current lead or pigtail 5 leading through a perforation in the cover. The 55

outer end of the pigtail is connected to the frame 1 by a contact member, as for instance a screw 6 and terminal lug 6'.

Tubular studs 7 are provided to support the brush holder frames 1, each of said studs 60 being disposed crosswise of the collector rings and being supported rigidly on the frame of the machine, not shown. Tubular insulating sleeves 8 are provided on each of said studs to prevent short circuiting of the 65 brush holders, or grounding thereof on the frame of the machine. Set screws or bolts 9 are used for clamping the split sleeves at each end of the frame to the brush holder studs 7. The inner ends of said studs are 70 carried by radially disposed arms 10.

Detachable fastenings such for instance as screws are provided on the brush holders, as shown at 11, for connecting the current supply leads or cables 12, which lead to the 75 source of current. The cable for the front brush holder enters the corresponding stud 7 at its forward or outer end, whereas the cable for the rear brush holder enters the other stud through a side aperture 13, shown 80 in Fig. 3.

The collector rings 14 are insulated from the hub 15 whereon they are mounted by a layer of insulation in the form of a sleeve 16.

It is to be noted that with this construction 85 the brush holders are arranged to present to the several rings a large area of multiple brush contact. The chambered frame 1 provides a dust proof housing for the brushes 2 and the positive direct-acting springs 90 thereof. The screw caps 3 permit ready adjustment and dependable setting. The parts are all easily accessible and interchangeable. Moreover the snug and secure housing for the current leads in the brush holder studs 95 is of especial advantage.

Although but one specific embodiment of this invention is herein shown and described, it is to be understood that numerous details of the construction shown may be altered 100 or omitted without departing from the spirit of the invention as defined by the following claims.

I claim:

1. A brush holder comprising an oblong 105 arcuate frame, provided with a plurality of brush boxes formed therein and a pair of supporting studs secured one to each end of said frame, one of said studs being tubular to house a current carrying lead for the 110

- brushes with which the holder is to be equipped.
2. A device of the character described comprising a multiple-box frame of oblong 5 arcuate shape, insulated supporting studs therefor, one at each end, and a conductor carried by one of said studs which is tubular, said conductor being connected electrically to said frame.
- 10 3. A device of the character described, comprising a multiple-box frame of oblong arcuate shape, means for supporting said frame at each end, brushes disposed one in each box, a conductor carried by one of said 15 supporting means and connected to said frame, and other conductors positively connecting the several brushes to said frame.
4. A multiple-box brush holder of substantially integral character having radially 20 positioned brushes arranged in arcuate alignment and electrically connected by said holder, each box including a threaded cylindrical flange part disposed radially outward from the main body of the holder and 25 formed integrally therewith, an adjustable threaded cap for the outer end of each box flange, and a spring helix disposed in compression between each brush and the corresponding cap.
- 30 5. A multiple-box brush holder of substantially integral character having radially positioned brushes arranged in arcuate alignment and electrically connected by said holder, each box including a threaded cylindrical flange part disposed radially outward 35 from the main body of the holder and formed integrally therewith, an adjustable threaded cap for the outer end of each box flange, a conductor connected positively to 40 each brush and to the brush holder frame, and a spring disposed in compression between each brush and the corresponding cap, said cap being centrally perforated to admit 45 said conductor axially of said spring.
6. In combination a plurality of insulated 50 collector rings disposed side by side, a pair of studs spaced outward therefrom, parallel with the ring axis and equidistant therefrom, and a plurality of oblong multiple-box brush holders disposed side by side 55 opposite said rings respectively, supported on said studs and insulated therefrom.
7. In combination a plurality of insulated 60 collector rings disposed side by side, a pair of studs spaced outward therefrom, parallel with the ring axis and equi-distant therefrom, and a plurality of oblong multiple-box brush holders disposed side by side 65 opposite said rings respectively, supported on said studs and insulated therefrom, said studs being tubular and insulated, and each brush holder having a conductor leading therefrom into one or another of said studs for conducting current to or leading it from the brush holder.
8. In combination a plurality of collector 70 rings, oblong brush holders therefor respectively, a pair of insulated tubular studs disposed side by side in spaced relation equidistant from the ring axis to support said brush holders, the latter having split sleeves at each end to grip said studs, and insulated conductors from said brush holders housed in said studs respectively, said studs being provided with insulating sleeves extending 75 through said split sleeves.
9. In combination a plurality of collector 80 rings, oblong brush holders therefor respectively, a pair of insulated tubular studs disposed side by side in spaced relation to support said brush holders, the latter having their ends formed to rigidly connect with the studs, said brush holders each having a plurality of radially positioned brush boxes, and said studs having tight fitting insulator 85 sleeves extending through the brush holder.

Signed at Mansfield, Ohio, this 25th day of June, 1920.

THEODOR SCHOU.
